UNITED STATES PATENT OFFICE.

PLATT B. VIELE, OF ROCHESTER, NEW YORK.

LEAK-STOPPER FOR VESSELS.

1,334,194.

Specification of Letters Patent. Patented Mar. 16, 1920.

Application filed January 20, 1919. Serial No. 272,145.

To all whom it may concern:

Be it known that I, PLATT B. VIELE, a citizen of the United States, residing at Rochester, in the county of Monroe and State of New York, have invented new and useful Improvements in Leak-Stoppers for Vessels, of which the following is a specification.

This invention relates to an improved means for stopping a leak in the hull of a ship and obstruct entrance of water into the hold of a vessel, and the primary object of the same is to provide a particular form of apron or ship bandage which may be readily applied to the injured part of the hull of a ship or vessel and held in fixed position over a hole or fractured portion of the hull as a temporary and effective means for obstructing the ingress of water into the vessel.

The invention consists in the construction and arrangement of the several parts which will be more fully hereinafter described and claimed.

25 In the drawings:—

Figure 1 is a perspective view of the improved leak stopper or bandage showing parts thereof broken away.

Fig. 2 is an end elevation of the hull of a ship broken away in part and shown in section with a hole therein and illustrating the improved leak stopper or bandage applied over the hole.

Fig. 3 is a longitudinal section through a portion of one of the side strips showing the manner in which the side strips and cross slats are assembled.

Fig. 4 is a horizontal section partially broken through taken in the plane of the line 4—4, Fig. 3.

Fig. 5 is a horizontal section taken in the plane of the line 5—5, Fig. 2.

The numeral 5 designates the hull of a vessel which is shown as having a hole 6 in the hull thereof below the water level.

The improved leak stopper, bandage or apron, particularly shown by Fig. 1, embodies side strips 7 having cross slats 8 terminally secured against one side thereof, the slats 8 overlapping, as at 9, to form tight joints. The slats are secured to the side strips 7 by means of headed bolts 10 engaged by nuts 11, the nuts being prevented from becoming accidentally disengaged from the bolt ends by means of a flexible strand or wire 12 inserted through the bolt

ends outside of the nuts and thereby providing a reliable nut lock and insuring a tight engagement of the overlapped slats 8 relatively to each other and the strips 7. 60 The strips 7 are provided with extra bolt holes 13, as shown, for application thereto of additional slats, if desired, and these strips may be made as long or as short as required in accordance with the general proportions of the improved device and the slats 8 may extend freely thereover or only partially over the same as they may be readily removed and replaced owing to the bolt and nut securing means therefor. The bottom slat is formed with a series of openings 14 extending longitudinally thereof and the lower bolt holes 13 of the strips 7 are left clear or these may be openings for a definite purpose which will be presently explained. The strips 7 may extend any distance above the uppermost slat 8 to form holders and are provided with blocks 15 secured thereon. The upper continuation of the strips 7 forming the holders 16 may extend any distance above the upper terminal of the hull or the rail of the latter and be secured by any suitable means after the improved stopper, bandage or apron is applied. The strips 7 and slats 8 are all 80

formed of metal, preferably spring steel, so as to enable the improved stopper, bandage or apron to conform to the curvature or roundness of the hull of the vessel to which the improved device is applied and thereby 90 form a tight joint of a non-leakable character with relation to the vessel's side, and particularly over the opening or hole that is formed in the vessel and which it is desired to cover to obstruct leakage of water into 95 the vessel hold. The strips 7 owing to their resiliency may bend longitudinally and the slats 8 may be made to conform either to a convex curvature or given a concave contour, so that they may be closely depressed 100 or extend into the hole or fracture of the hull of the ship or vessel, as shown, for instance, by Fig. 5, and when these slats are forced tightly into the outer portion of the hole or opening in the vessel or hull a very 105 tight engagement will be set up between the slats and the surrounding edge of the hole. To draw the slats inwardly into the hole in a vessel's side, as shown by Fig. 5, a ring or eye 17 is secured to one of the slats and 110 will have a chain or analogous device 18^a attached thereto and secured against the in-

terior of the vessel hull so as to maintain a tight joint between the slats and the edge of the opening in the hull. It will be understood that by drawing inward on one of the 5 slats, the adjacent slats will likewise be forced inwardly owing to the overlapping association of the slats and, if desired, any number of these rings may be employed and applied where found necessary or to the 10 best advantage in holding the improved device in applied or leak-preventing position.

To the lower portion or extremity of the improved stopper, bandage or apron a stay chain or analogous device 18 is secured and 15 provided with two lateral branches 19 attached in two of the holes 14, as shown in Fig. 1, the branches 19 extending from a ring 20 to which the chain 18 is also attached. The stay chain 18 is passed around 20 below and over the keel of the vessel and upwardly over the outer side of the hull opposite that to which the stopper, bandage or apron is applied and secured, as illustrated in dotted lines by Fig. 2, said stay 25 chain operating to hold the stopper, bandage or apron downwardly over the hole or fracture in the hull of the vessel and to assist in maintaining a water-tight joint by closely drawing the lower portion of the improved device against the hull of the vessel below the hole or fracture therein. To prevent 30 lateral displacement of the improved device when applied oppositely extending or lateral stay chains 21 are secured to a ring 22 interposed in the chain 18 below the ring 20 and also passed through the lowermost openings 13 in the strip 7. These lateral stay chains 21 may be of any suitable length and are extended upwardly over the hull of the vessel 35 above the hole or fracture therein and secured at the top portion of the hull. In addition to preventing lateral or sidewise movement of the device when it is applied over the hull or fracture in the vessel hull the lateral stay chains 21 serve to hold the lower ends of the strips 7 and the adjacent parts thereof as well as the lowermost slats 40 closely against the surface of the hull and thereby add to the effectiveness of the water-tight seal formed by the improved device when applied.

In applying the improved stopper, bandage or apron over a hole or fracture in the hull of a vessel it is lowered from the vessel 45 deck close to the hull side and the stay chain 18 is drawn upwardly at the opposite side of the hull deck to sufficiently depress and provide for a proper application of the improved device and the holders 16 are then secured to prevent rising and falling movements of the improved stopper, bandage or apron. The stay chains 21 are drawn taut 50 and the holders 16 are pressed closely against the side of the hull in which the hole or fracture is formed and the pressure of the

water against the outer sides of the slats 8 and of the strips 7 will force the improved device as a whole closely inwardly against and over the fracture to form a water-tight leak-stopper means, and from the interior of 70 the hole the application of the improved device may be easily completed by drawing inwardly on the chain 18^a and fastening the latter.

When the improved device is not in use, 75 it may be readily raised and held on the side of the hull or stored on the deck of the ship, it being intended to make the stay chain 18 long enough to permit this storage or upward maximum movement of the improved 80 device when not in service. It will be understood that the stay chain 18 will be applied around and beneath the vessel hull at a time prior to when it becomes necessary to use the improved leak-stopper, bandage or 85 apron, so that the latter may be instantly drawn over the hole or fracture formed in the hull of the vessel. It is also proposed to shift the improved leak stopper, bandage or apron along the length of the side of the 90 hull of the vessel and one of the improved devices may be preliminarily applied for 95 operation and service on opposite sides of the hull or there may be a number of these devices arranged for service on the same side of the hull so as to thereby cover one or more 100 openings or fractures. The improved device is easily handled and may be readily applied in operative position and it is proposed to modify the general dimensions and proportions thereof as may be found necessary and desirable to suit the hulls of various 105 types of ships or vessels.

What is claimed is:—

1. A device of the class set forth comprising opposite side strips having a plurality of openings therein, a series of overlapped cross slats terminally secured against one side of the side strips and held in fixed applied positions, the side strips being provided with 110 openings in addition to those required for the slats applied to permit an increase of the 115 number of slats through the application to the side strips of additional slats, bolts and nuts removably securing the ends of the slats to the cross strips, the bolts having flexible means inserted through the ends thereof, and stay means secured to the lower extremity of the device to extend beneath and upwardly over the side of a vessel and 120 also laterally to hold the device in applied position, the device also having means for suspending the same from the upper end thereof, the slats and the side strips being 125 flexible to adapt a ready conformation thereof to the opening over which they may be applied.

2. A device of the class specified comprising side strips, closely overlapping slats secured at their ends to the strips in fixed posi- 130

tions, the slats and strips being formed of resilient metal to adapt them to conform to various curvatures, and stay means connected to the lowermost slat and to the lower extremities of the side bars and united for holding the device in fixed applied position both vertically and laterally.

3. A device of the class specified comprising side strips, a plurality of slats secured to the said side strips and having overlapping edges, the slats being immovable and both the side strips and slats being formed of resilient metal, the side strips being extended above the uppermost slats to serve as holders and stay means adjustably connected to the

lowermost slat and also engaging the lower extremities of the side strips, the stay means from the lower slat being connected to the stay means engaging the side strips and being extended beneath and upwardly over the side of a vessel, the stay means engaging the side strips being extended laterally from the said side strips.

In testimony whereof I have hereunto set my hand in presence of two subscribing witnesses.
